UNITED STATES PATENT OFFICE.

ANDREW F. CURTIN, OF MEDFORD, MASSACHUSETTS.

FLUSHING-VALVE.

1,270,018.

Specification of Letters Patent. Patented June 18, 1918.

Application filed April 4, 1917. Serial No. 159,773.

To all whom it may concern:

Be it known that I, ANDREW F. CURTIN, a citizen of the United States, residing at Medford, in the county of Middlesex and 5 State of Massachusetts, have invented certain new and useful Improvements in Flushing-Valves; and I do hereby declare the following to be a full, clear, and exact description of the invention, such as will enable 10 others skilled in the art which it appertains to make and use the same.

The present invention relates to an improvement in flushing valves for water-closets.

15 The object of the invention is to reorganize the construction and arrangement of the parts of a water-closet flushing valve in order to produce a more efficient and durable flushing valve than has hitherto been produced. To the accomplishment of this object and such others as shall hereinafter appear, the present invention consists of the improved flushing valve described in the following specification and particularly pointed out in the appended claims.

20 The preferred form of the invention is illustrated in the accompanying drawings, in which Figure 1 is a sectional elevation of the improved flushing valve; Fig. 2 is 25 a section taken on the line 2—2 of Fig. 1; and the upper part of Fig. 3 is a vertical section taken on the line 3—3 of Fig. 1, while the lower part of Fig. 3 is a vertical section of a bowl, in connection with which 30 the improved flushing valve is used.

As shown in the upper part of Fig. 3, the improved flushing valve is adapted to be located within the usual tank or reservoir 4 secured to the wall 5 of the room 40 and located a convenient distance above the bowl 6. The tank is supplied with water through the usual ball cock. The tank is made air tight by means of a cover 7 and gaskets 8. The hollow body portion 9 of 45 the valve is somewhat elliptical in outline, as shown in Fig. 2, and is provided on the bottom with a downwardly projecting discharge pipe 10 adapted to be received in a hole in the bottom of the tank 4. A check- 50 nut 11 holds the valve body 9 in fixed position in the tank. Threaded onto the lower end of the discharge pipe is a pipe 12 which connects the flushing valve with the bowl.

In one end of the upper surface of the 55 valve body 9 of the flushing valve is formed

an outlet 13 through which the water passes from the tank into the hollow valve body, whence it passes through the discharge pipe 10 down through the pipe 12 to the bowl 6. The upper rim 14 of the tank outlet 13 constitutes a valve seat, adapted to receive a 60 resilient disk 15 secured in place in the lower end of a tank outlet closing member or valve proper 16 having a threaded central boss 17. The resilient disk 15 is held in place 65 on the valve 16, as shown in Fig. 1, by a bolt 19 having a disk-like head 20. The upper end of the stem 21 of the bolt 19 contains a hole, in which is loosely received the lower end of a rod 22, the upper end 70 of which is loosely received in a hole in one end of a lever 23 pivoted at 24. The outer end 25 of the lever 23 projects from the tank and affords means by which the lever may be manipulated to raise the valve 16 75 to open the tank outlet 13 to permit the water from the tank to flush the bowl 6. The range of movement of the valve 16 is shown in dotted lines in Fig. 1. The valve 16 is guided in its up and down movements 80 by an open framework having guide bars 27 rising from the valve body. An overflow pipe 29 is threaded into the upper part of the valve body 9, and on its upper end a collar 30 is threaded which supports a 85 bracket 31, upon which the lever 23 is pivoted.

By reference to Fig. 3 it will be observed that the construction and arrangement of the parts thus far described are such that 90 a free air passage exists from the interior of the bowl by way of the pipe 12 and up into the interior of the flushing valve, and from thence up through the overflow pipe 29 into the upper part of the tank 4, into 95 which there opens above the water level a vent 33 which discharges into the chimney or by a separate pipe into the atmosphere. Thus there is provided a simple and efficient 100 ventilating system for ventilating the bowl 6.

In order to keep the valve 16 raised from the valve seat 14, while the water is passing from the tank 4 into the hollow valve body 9 of the flushing valve, a spoon-like valve control member or governor 35 is provided, 105 located within the valve body and pivotally mounted therein on a pin 36, the outer ends of which are fulcrumed in bosses in the side walls of the valve body. In plan the outline of the governor 35 is like the valve body, as 110

shown in Fig. 2, a sufficient space 34 being left between the two for the flow of the water as it passes from the tank outlet around the governor to the discharge pipe 10. Caps 37 are threaded onto the outer ends of the bearing bosses and are provided with interposed resilient washers 38 to prevent leakage. The governor 35 is loosely pivoted on the pin 36, and the pin 36 is loosely fulcrumed in its bearing bosses in order to reduce friction. To prevent cramping of the governor on its pivot pin, the governor is provided with a long hub 39, sufficient end-play being allowed between the ends of the hub and the inner surfaces of the side walls of the valve body. By reference to Fig. 1 it will be seen that the right-hand end of the governor, which is that part situated immediately under the tank outlet, is hollow, and that at this end it is completely inclosed on its upper part by the surface 43. An opening 40 at the other end of the governor is provided leading into the interior thereof, so that water may pass into the hollow body portion of the governor for a purpose presently to be described. The governor is loosely connected with the lever 23 by means of a link 41, which passes through the overflow pipe 29. When the flushing valve is in normal condition and the valve 16 is seated, the governor is thereby compelled to assume the position shown in full lines in Fig. 1; and when the flushing valve is operated to permit the flushing of the bowl 6, the governor assumes the position shown in dotted lines in Fig. 1.

When the lever 23 has been oscillated to raise the valve 16 to permit the water in the tank to flow down through the discharge pipe 10 into the bowl 6, the oscillation of the lever 23 causes the left-hand end of the governor to be raised and its body portion to be depressed. Thereupon, as the water pours down through the tank outlet 13, it descends onto the upper surface 43 of the governor, and the force of this fall of water is such that until the tank is emptied to a predetermined extent, the governor is maintained in the position shown in dotted lines in Fig. 1, and therefore the valve 16 is held unseated after the lever has been released. While the water is pouring down through the tank outlet and dashing on top of the surface 43 to maintain the governor in operative position, a small part of the water is pouring down through the inlet 40 and filling the hollow body portion of the governor. The weight of this water in the body portion of the governor aids in keeping the governor in its operative position. A small outlet aperture 44 in the bottom of the governor permits the water to run out therefrom. A stop 45 formed on the lower surface of the governor is adapted to come into

contact with the corner of the entrance of the discharge pipe 10, to determine the operative position of the governor.

The above-described construction of flushing valve is such that when the valve 16 has been unseated by an oscillation of the lever 23 to permit the water to pass out of the tank into the bowl, and the governor has thereby been moved from its inoperative position, as shown in full lines in Fig. 1, to its operative position, as shown in dotted lines, the governor is held in this position by the force of the stream of water against it until the tank is substantially emptied, thereby keeping the valve 16 raised and the tank outlet 13 open. While the water is passing from the tank through the body portion 9 of the flushing valve out through the discharge pipe 10, some of it, as before stated, finds its way into and fills up the interior of the governor through the opening 40. The force of the water falling on the surface 43 maintains the governor in its operative position and the valve 16 unseated until a predetermined level in the tank is reached by the recession of the water therefrom. Then when the flow of the water has decreased to such an extent that the force of the water pouring onto the surface 43 would be insufficient to maintain the governor in operative position, the weight of the water contained within the governor is sufficient for holding the governor in operative position, and thereby holding the valve 16 unseated while the rest of the water in the tank is flowing out to cause the refill of the bowl. During this bowl refilling process, the water within the governor is slowly draining therefrom through the aperture 44, so that by the time the bowl is refilled the governor is emptied. Thereupon the latter rises and the valve 16 descends to close the tank outlet to permit the tank to be refilled.

Having thus described the invention, what I claim as new is:

1. A water-closet having, in combination, a flushing valve comprising a valve proper, a lever connected with the valve proper for actuating it, a valve control member pivoted within the body portion of the flushing valve arranged to receive the force of the water when the valve is opened and to hold the valve open for a predetermined length of time, and connections between the lever and the valve control member.

2. A water-closet having, in combination, a flushing valve comprising a valve, a lever connected with the valve for actuating it, an overflow pipe having entrance into the body portion of the flushing valve, a valve control member pivoted within the body portion of the flushing valve, and a link located within the overflow pipe connecting the lever with the valve control member.

3. A water-closet having, in combination,

a flushing valve comprising a valve, a hollow valve control member having a relatively large inlet and a relatively small outlet, situated within the body portion of the flushing valve, and connections between the valve control member and the valve, the construction and arrangement of these parts being such that when the valve has been unseated to permit water to fall on the valve

control member, the valve is thereby held 10 unseated by the force of the water thereagainst until the force of the water is insufficient to hold the valve unseated, whereupon the weight of the water in the valve control member holds the valve unseated for 15 a predetermined time.

ANDREW F. CURTIN.
